UNITED STATES PATENT OFFICE.

SAMUEL R. KING, OF BOSTON, MASSACHUSETTS.

FIRE ESCAPE OR LADDER.

SPECIFICATION forming part of Letters Patent No. 511,438, dated December 26, 1893.

Application filed July 7, 1890. Serial No. 357,996. (No model.)

To all whom it may concern:

Be it known that I, SAMUEL R. KING, a citizen of the United States, residing at Boston, in the county of Suffolk and State of Massachusetts, have invented certain new and useful Improvements in Fire Escapes or Ladders, of which the following is a full, clear, and exact description, reference being had to the accompanying drawings, making part 10 of this specification, in which—

Figure 1 is a side elevation of my improved fire-escape and ladder folder upon its truck. Fig. 2 is a plan of the same. Fig. 3 is a plan of the under side of the supporting platform or truck of the apparatus. Fig. 4 is a side elevation of the lower part of the apparatus with the ladders extended upward. Fig. 5 is a front elevation of the same. Fig. 6 is an enlarged vertical transverse section through the 20 lower portion of the apparatus. Fig. 7 is a detail in perspective of a portion of the lazy-tongs, showing one of the platforms or landings which extend across the space between the meeting ends of the ladders. Fig. 8 is a 25 plan of said platform showing the position of its extensible support when the lazy-tongs are folded together. Fig. 9 is a vertical transverse section of the platform or landing. Fig. 10 is a detail in perspective of one of the pivotal roller-bearings employed at the point where the two crossed ladders of a section are 30 jointed together. Fig. 11 is a rear view of the apparatus. Fig. 12 is a detail in perspective of one of the sections of the lazy-tongs, 35 showing the bridges in position under the ladders and against the rungs of the same. Fig. 13 is a perspective view of the apparatus extended upward in front of a building and ready for use.

40 My invention has for its object to improve the construction of fire-escapes and ladders embodying the principle of the lazy-tongs, and adapted to be compactly folded or extended upwardly as the lower members or 45 risers are separated or moved toward each other, in a well known manner.

To this end my invention consists in certain novel combinations of parts and details of construction as hereinafter described, 50 whereby the strength and efficiency of the apparatus are materially increased and better facilities afforded for persons escaping from

a building to descend without interfering with the firemen who may be engaged in their duties upon the apparatus.

55 In the said drawings, A represents the supporting platform or truck of the apparatus, which is mounted on wheels and adapted to be drawn by horses as usual. This platform A, consists of a series of longitudinal bars 60 a, securely fastened together by transverse pieces b, the spaces c between the upper and lower bars a, forming guideways within which are placed grooved wheels d, secured to axles or carriers B, B, extending transversely across 65 the platforms as seen in Fig. 6. To the central portion of each of the axles B, is secured a heavy block or casting D provided with a threaded aperture f, through which passes a long horizontal screw shaft E, mounted in 70 bearings on the underside of the platform A, and extending from one end to the other of the same, said shaft being provided at the rear end with a removable crank h, and gears i, k, as seen in Fig. 11, whereby it may be rotated. This shaft E is provided on opposite 75 sides of its center with right and left hand threads engaging with similar threads in the blocks D, D, by which construction when the screw shaft E is rotated, the axles B, B, will 80 be simultaneously drawn toward each other or separated in accordance with the direction of rotation of the said screw shaft.

Upon the axles B, B, are pivoted the lower members or risers of a system of lazy-tongs 85 which are composed of a series of crossed ladders G, each pair of crossed ladders being pivoted together at the center by means of rods or shafts p passing through the side pieces of the two ladders which form a section of the 90 lazy-tongs. The meeting ends of the four ladders which form adjoining sections of the lazy-tongs are jointed to each other by transverse rods or shafts q, which take the place of rungs or rounds at the points where they 95 pass through the sides of the ladders. The pivots by means of which two ladders of a section are jointed together, are preferably provided with roller bearings 15 as seen in Fig. 10, whereby the friction at these points 100 is reduced to a minimum, but as these bearings are of ordinary and well known construction, they will not be herein more particularly described.

Outside the ladders on each side of the apparatus, are placed auxiliary strengthening or supporting bars or risers K, of the same length as the ladder, and jointed thereto on the same bolts or pivots by which the meeting ends of the ladders are fastened together. These auxiliary bars or risers K serve to strengthen and stiffen the structure when extended, and form a part of the system of lazy-tongs, being arranged parallel with the ladders and adapted to fold up or be extended upward therewith. When the axles or carriers B, B, are moved apart by means of the screw-shaft E above described, the ladders forming the members or risers of the lazy-tongs will lie parallel with each other and be compactly folded together upon the truck or platform A, as seen in Fig. 1, ready to be drawn to the scene of the fire, but when the axles B, B, are moved toward each other, as shown in Figs. 4 and 13, the ladders will be extended upwardly to the desired height to bring them into a proper position to afford a ready means of descent or ascent as may be required.

Fire-escapes constructed on the principle of lazy-tongs have heretofore been composed of parallel side bars or risers jointed together in the usual manner, and each section has been provided with a single ladder arranged between the two pairs of risers forming each section of the lazy-tongs. By my construction however, in which the members of the lazy-tongs are composed of crossed ladders as described, many advantages are gained, as the apparatus is simplified, and rendered stiffer, stronger, and safer, while two wide ladders are provided for each section instead of one, thus offering increased facilities for escape from a burning building, and also enabling persons going in opposite directions to pass each other upon the apparatus much more easily than before, so that in escaping from a building the descent can be made without interfering with the firemen who may be engaged in their duties upon the apparatus.

Between the meeting ends of the ladders or risers of each section of the lazy-tongs is placed a horizontal landing or platform L, which when the lazy-tongs are extended upward, will reach across the space between the upper ends of each X or section formed by said ladders, and rest at its opposite ends upon the rungs q, q, of the same as seen in Fig. 7, one end of said platform being permanently jointed to one of said rungs, while the opposite end merely rests upon the ladder-rung at the opposite end of the space over which it extends. This platform L instead of being made to swing vertically upward between the risers of the lazy-tongs as heretofore when the latter are to be folded, is caused to remain constantly in a horizontal position, in which position it is held by an extensible supporting device M, composed of a series of bars arranged side by side and adapted to slide one upon the other as seen in Figs. 8 and 9,

said bars being provided with dovetail tongues and grooves at the edges and being held together by straps 20. One of the bars r of the extensible support M is secured to the under side of the landing or platform L, while the bar s on the opposite side is permanently secured to the ladder rung q on the opposite side of the space over which the platform is intended to extend, as seen in Fig. 8, and thus when the ends of the ladders G of each section are moved apart in folding them together, the bars of the support M will slide outward upon each other, thus maintaining the platforms always in a horizontal position, and when the ladders are again raised and their upper ends brought toward each other, the bars of the support M will slide inward upon each other and shut together until the end 21 of the platform or landing L supported thereby rests firmly on the opposite rung q of the ladder as desired. The operation of these platforms is thus rendered perfectly automatic so that they are always in place when the ladders are raised, while the chains or ropes and pulleys hitherto employed to raise and lower the platforms at these points are dispensed with, thus materially simplifying the construction of the apparatus.

When the apparatus is raised as shown in Figs 12 and 13, communication between the ladders and the buildings is established by means of bridges or ladders P detachably pivoted at their lower ends between the side pieces of the main ladders which form the members of the lazy-tongs. This may be effected by providing the lower ends of the bridges with hooks 22 adapted to fit over the rungs of the ladders as shown in Fig. 12, which rungs would then preferably consist of iron rods. These bridges P are so arranged that they will descend by their own gravity onto the building as seen in Figs. 12 and 13 when permitted to do so by slackening a rope or chain w attached to the upper end of each one and passing down over suitable pulleys a' to the truck or platform A. Each of the ladders G of the lazy-tongs is preferably provided with one of these bridges P whereby communication can be established with the building on either side and at different levels, it being merely necessary to let down the particular bridge which lies nearest to the point to be reached. The arrangement of the bridges P between the side pieces of the main ladders enables them to be swung or drawn up by their ropes or chains out of the way under the ladders as seen in Fig. 12 when not required for use, in a position that will not interfere with the free passage of a person over the ladders, or with the folding up of the same, while they can be readily let down onto the building when required for use, their outer ends being preferably provided with hooks, as seen in Figs. 1, 9, and 12. As before stated, the bridges P are detachably connected at their lower ends with the main ladders, whereby should the truck A happen

to be so placed that a bridge P could not be dropped onto the building by slackening its rope w, it can be disconnected and made to extend in any desired horizontal direction 5 from one of the landings L.

What I claim as my invention, and desire to secure by Letters Patent, is—

1. In a fire-escape, the combination of the supporting platform or truck, the lazy-tongs, 10 the risers or members of which are composed of crossed ladders pivoted together as described, and the outer auxiliary jointed supporting bars or risers K arranged on opposite sides of the structure outside the ladders, and 15 adapted to support and strengthen the same, substantially as set forth.

2. In a fire-escape, the combination with the lazy-tongs composed of crossed ladders

pivoted together as described, of the landings or platforms L extending horizontally 20 across the spaces between the meeting ends of the risers or members of the lazy-tongs, and having the extensible supports M composed of bars sliding upon each other as described, and connected with the platform and 25 the meeting ends of the ladders, whereby the platforms are supported horizontally while the ladders are being folded or extended, substantially as set forth.

Witness my hand this 1st day of July, A. D. 30
1890.

SAMUEL R. KING.

In presence of—

P. E. TESCHEMACHER,
HARRY W. AIKEN.
